Patented Jan. 25, 1921.

UNITED STATES PATENT OFFICE.

DANA OSGOOD, OF HOPEDALE, MASSACHUSETTS, ASSIGNOR TO DRAPER CORPORATION, OF HOPEDALE, MASSACHUSETTS, A CORPORATION OF MAINE.

WARP STOP-MOTION FOR LOOMS.

1,366,828.

Specification of Letters Patent. Patented Jan. 25, 1921.

Application filed July 14, 1920. Serial No. 396,142.

To all whom it may concern:

Be it known that I, DANA Osgood, a citizen of the United States, residing at Hopedale, county of Worcester, and State of Massachusetts, have invented Improvements in Warp Stop-Motions for Looms, of which the following description, in connection with the accompanying drawings, is a specification, like characters on the drawings representing like parts.

This invention relates to warp-stop-motions for looms, and more particularly to means for locating and finding the broken or abnormal warp thread which has caused the loom to stop.

Looms are now usually provided with warp-stop-motions which comprise a series of warp detectors or drop wires which ordinarily hang upon the warp threads between the whip rolls and shedding mechanism, and when one of the warp threads breaks or becomes too slack, the warp detector or drop wire which is controlled by that thread, is permitted to drop or come into a position to cause loom stoppage. Owing to the large number of warp threads employed in a loom, the inconspicuous character of the warp detectors, and other features, the weaver finds it difficult to locate the abnormal warp thread which has caused the loom to stop, and much loss of time is incurred by the weaver in locating and piecing up the broken warp thread or taking up the slack thereof.

An important feature of the present invention, therefore, consists of means under control of the weaver for readily finding the defective or abnormal warp thread and for enabling the weaver to readily piece up or take up the slack in the abnormal warp thread.

The warp detectors or drop wires, and the particular means for stopping the loom when a warp detector is released or dropped by a broken or unduly slack warp thread, may be variously constructed, and a number of different types of warp detectors and stopping mechanisms are now well known. In the present invention, however, the drop wires are formed of metal and guided for vertical movement relative to the guiding means, and the stopping mechanism includes toothed bars, one of which is normally stationary and the other of which is normally reciprocated during the operation

of the loom, the construction and arrangement being such that should a warp detector drop, it will engage the teeth of the bars and arrest the movement of the reciprocating bar by locking the two bars together. 60

When the loom has been stopped, as above indicated, the warp finder which is under manual control of the weaver, may be actuated to move both of the toothed bars and with them the interlocked and positively held warp detector in a direction laterally of the loom, the effect being that the detector moves the other detectors adjacent thereto and opens up the sheet of warp threads so that the weaver may readily find the abnormal warp thread and remedy the defect. 70

The invention will be best understood from the following description and accompanying drawings of one good practical form thereof. 75

In the drawings:

Figure 1 is a perspective view of a warp-stop-motion embodying the present invention with some of the parts being shown in section, and others broken away; 80

Fig. 2 is an enlarged detail sectional view showing the manner of actuating the warp finder and locating the abnormal warp thread;

Fig. 3 is a plan view showing the effect 85 of actuation of the warp finder when a warp detector is locked by the toothed bars.

It has not been deemed necessary herein to describe the loom frame or the operating parts of a loom, nor the particular means 90 for supporting the warp-stop-motion in position between the whip rolls and shedding mechanism, because these features of construction are well known in the art and their particular details form no essentials 95 of the present invention.

The warp-stop-motion may be connected to the loom frame by supports 1, one at each side of the loom, and extending between the supports 1 are the normally stationary and 100 normally reciprocating toothed bars which are adapted to be locked together when a warp detector drops.

In the present instance of the invention the normally stationary toothed bar 2 is 105 provided with a longitudinally extending slot or guide-way 3 in which may conveniently be located the normally reciprocating toothed bar 4. The toothed bar 2 may have two series of teeth 5, one series at each 110

side of the series of teeth 6 of the reciprocating bar, but this may not always be necessary, although it is a convenient and good practical form of this feature of the invention.

It is now the usual practice to arrange the warp detectors in two transversely extending columns in order to avoid crowding of the detectors by the closely adjacent warp threads. In the present instance of the invention the warp detectors are arranged in two columns or rows transversely of the loom, and, consequently, there are two sets of toothed bars, one set to coat 10 with each of the columns or rows of detectors.

The normally stationary toothed bars 2 are connected together at their ends by a spacing piece 7 and are supported between 20 the side members 8 of a bracket 9 appropriately secured to the supports 1 at each side of the loom. At one end the normally stationary toothed bars 2 are further connected by a cross-piece 10, Fig. 1, through which 25 extend the stems or pins 11 which are secured to the normally stationary toothed bars 2. The pins 11 extend through a riser 12 extending upwardly from the bracket 9, as indicated at the left in Fig. 1. Springs 30 13 placed about the guide pins 11 and between the riser 12 and the cross-piece 10, serve normally to yieldingly impel the normally stationary toothed bars 2 to one side of the loom but with permissive movement 35 of such toothed bars laterally of the loom in opposition to the force of the springs.

In order to provide for different widths of looms and the adjustment of the brackets 9 thereto, the brackets 9 may be connected to 40 the supports 1 by slots 14 and bolts 15, one example of which is indicated at the left, Fig. 1.

The opposite ends of the normally stationary toothed bar 2, as hereinbefore stated, 45 are connected together by the spacing block 7 and the ends of the toothed bars 2, at the right, Fig. 1, rest between the side members 8 of the bracket at that side of the loom, the construction being such that the toothed bars 2 may be moved laterally in the guiding brackets at the opposite sides of the loom.

The reciprocation of the toothed bars 4, which may be conveniently located in the central longitudinal guide-way of the fixed 55 bars 2, may be imparted by any of the well-known mechanisms now in use. In the present instance the two bars 4, see the left in Fig. 1, are connected by a pin 16 which passes through suitable slots 17 formed in 60 the toothed bars 2. Between the toothed bars 2 the pin 16 is engaged by the bifurcated end 18 of a rocker arm 20 which may be mounted upon a pin 21 supported by the bracket 9. The rocker arm 20 is appropriately actuated by any usual form of warp-

stop-motion mechanism through the rod 22, which connects with the arm 23 of the rocker, the construction being such that should the reciprocating movement of either of the reciprocating bars 4 be arrested during loom operation by a warp detector interlocking with the teeth of the relatively fixed and reciprocating bars, the loom will be stopped. It has not been deemed necessary to illustrate the stopping mechanism 75 connected with the rocker arm, since such mechanism is well known in the art and its details form no essential part of the present invention.

Mounted upon the brackets 9 are the 80 guide supports 24, one of which is shown at the right, Fig. 1. The guide supports 24 have secured thereto the parallel rods 25, two of which are used when two rows of warp detectors are employed, as in the present instance. Also connected to the guide supports 24 are the warp supporting rods 26 over which the warp threads *a* pass as they travel from the warp beam toward the shedding mechanism. The warp detectors 27 may be of various construction but in the present instance they are shown as provided with an elongated slot 28 through which the guide bars 25 are passed and each detector is provided with a warp eye 29 to 28 receive a warp thread and by which the warp threads serve to support the detectors in operative or raised position when the warp threads are unbroken and normal. The warp finder for moving the normally 100 stationary toothed bar 2 and the normally reciprocating bar 4 in a direction transversely of the loom, and with them the interlocked dropped warp detector, may be variously constructed, but in the present instance of the invention the warp finder consists of a wedge-shaped block 30, Figs. 1 and 2, which extends downwardly through the end portion of the bracket 9, as will presently appear, and by actuation of the 105 finder the normally stationary and reciprocating toothed bars may be moved transversely of the loom when the loom is stopped.

The warp finder 30 has a straight side 110 which may preferably bear upon the plain vertical surface of a cross member 31, joining the two side guiding flanges 8 of the bracket 9, and may also have at its opposite side an incline 32 adapted to engage a similar incline 33 on the spacing block 7 connecting the two normally stationary toothed bars 2. The warp finder or wedge 30 is guided in its operating movements, and to this end suitable guiding means are employed. In the present instance a pin 34 is adjustably secured to the bracket 9 and extends upwardly into a hole 35 in the warp finder. A spring 36 surrounds the rod 34 and normally forces the warp finder or 120

wedge upwardly. The construction is such that when a warp detector drops, it will engage the teeth of the relatively fixed and reciprocating toothed bars and thereupon arrest the reciprocating bar and cause the loom to stop, as usual in this class of warp-stop-motions. The dropped warp detector is then gripped positively between the teeth of the two bars and by manual actuation of the warp finder 30, the weaver moves the normally stationary, but yieldingly held toothed bars 2, transversely of the loom and, perforce, also moves the interlocked toothed bar 4 and dropped warp detector. The effect of this is that the warp detector will be moved laterally somewhat from its usual working position, substantially as indicated in Fig. 3, and the separation of the detectors in the row and the warp threads, will at once indicate to the weaver the source of trouble. With one hand he may then engage the dropped warp detector and then release the warp finder 30, whereupon the latter returns to initial position and at the same time the toothed bars 2 and 4, and the dropped detector, move back or transversely to their original or initial position, so that as soon as the weaver has corrected the faulty warp the loom is ready to start.

30 Claims—

1. In a warp-stop-motion for looms, the combination of a series of warp detectors, relatively movable toothed bars, means for reciprocating one of said bars and effecting loom stoppage when its reciprocating movement is arrested by a dropped detector, and different means for moving both of the toothed bars longitudinally when they are locked together by a dropped detector.
2. In a warp-stop-motion for looms, the combination of a series of warp detectors, relatively movable toothed bars constructed and arranged to be locked together by a dropped warp detector to stop the loom, and manual means operable while the loom is at rest for moving both bars longitudinally and with them the dropped detector when they are locked together.
3. A warp-stop-motion comprising, in combination, a series of warp detectors, a yieldingly mounted toothed bar and a reciprocating toothed bar constructed and arranged to stop the loom when relative movement of the bars is prevented by a dropped detector, and manual means operable while the loom is at rest for moving both bars and the dropped detector laterally of the loom.
4. A warp-stop-motion, comprising, in combination, a series of warp detectors, a normally stationary toothed bar and a reciprocating toothed bar constructed and arranged to be locked together by a dropped warp detector to stop the loom, and a manually actuated warp finder for moving the normally stationary toothed bar laterally of

the loom and with it the other toothed bar and interlocked warp detector.

5. A warp-stop-motion for looms, comprising a series of warp detectors, two toothed bars which are relatively movable longitudinally, constructed and arranged to be locked together by a dropped detector to arrest the movable bar and effect loom stoppage, and a warp finder for moving one of the toothed bars longitudinally and with it the other toothed bar and the interlocked dropped warp detector.

6. In a warp-stop-motion for looms, the combination of a series of warp detectors, means operable by a moving part of the loom for positively grasping a dropped detector, and different means for moving the grasping means and dropped detector laterally of the loom when the loom has been stopped.

7. In a warp-stop-motion for looms, the combination of a series of warp detectors, toothed bars both of which are mounted for longitudinal movement transversely of the loom frame, means for relatively reciprocating the toothed bars and for stopping the loom when such relative reciprocation is arrested by a dropped warp detector engaging the teeth of both bars and locking them together, and a manually actuated device for moving the normally stationary toothed bar longitudinally and with it the other toothed bar and the positively gripped warp detector held by the teeth of both bars.

8. In a warp stop motion for looms, the combination of a series of warp detectors, a normally stationary toothed bar extending transversely of the loom and supported at its ends for movement in a longitudinal direction, a normally reciprocating toothed bar adapted to be arrested in its movement and locked to the normally stationary bar by a dropped detector, and manually operable means located at one end of the normally stationary bar for moving both bars longitudinally when they are locked together to indicate the position of the abnormal warp thread.

9. In a warp stop motion for looms, the combination of spaced rows of warp detectors, a pair of normally stationary toothed bars supported at their ends upon the loom for longitudinal movement, a normally reciprocating toothed bar adjacent each normally stationary toothed bar and adapted to be arrested in its reciprocating movement and locked to the adjacent normally fixed bar by a dropped detector, and manually operable means at one end of the normally stationary bars for moving the normally stationary bars and reciprocating bars longitudinally when they are locked together to indicate the position of the abnormal warp thread.

10. In a warp stop motion for looms, the combination of a series of warp detectors,

- 5 a normally stationary toothed bar and a normally reciprocating toothed bar extending transversely of the loom and adapted to be locked together against relative movement by a dropped detector, and wedging means for moving said bars longitudinally when they are locked together by a dropped detector to indicate the position of the detector.
- 10 11. In a warp stop motion for looms, the combination of a series of warp detectors, a normally reciprocating toothed bar and a normally stationary toothed bar adapted to be locked together by a dropped detector, and manually operated means located adjacent the end of said toothed bars for moving them longitudinally when they are locked together by a dropped detector.
- 15 12. In a warp stop motion for looms, the combination of warp detectors, a normally stationary and a normally reciprocating toothed bar adapted to be locked together by a dropped warp detector, and a bar shifter adapted to be operated at will and 20 acting upon said bars to move them longitudinally when they are locked together by a dropped detector and the loom is at rest.
- 25 13. In a warp stop motion for looms, the combination of warp detectors, a normally stationary and a normally reciprocating toothed bar adapted to be locked together by a dropped warp detector, and a bar shifter 30 at one side of the loom having a cam surface adapted to be operated at will and acting upon said bars to move them longitudinally when they are locked together by a dropped detector and the loom is at rest.
- 35 14. In a warp stop motion for looms, the combination of a series of warp detectors, a yieldingly mounted normally stationary toothed bar and a normally reciprocating toothed bar adapted to be locked together by a dropped detector, and a bar shifter mounted adjacent one end of the toothed bars and adapted to be actuated manually to 40 shift the bars longitudinally when they are locked together by a dropped warp detector.
- 45 15. In a warp stop motion for looms, the combination of a series of warp detectors, a reciprocating toothed bar operatively connected to a moving part of the loom and a normally stationary toothed bar, said bars constructed and arranged to be locked together by a dropped warp detector to arrest the movement of the reciprocating bar, and 50 means operable independently of said moving part of the loom for moving the normally stationary toothed bar laterally of the loom and with it the other toothed bar and interlocked warp detector to indicate 55 the position of the abnormal warp thread.
- 55 In testimony whereof, I have signed my name to this specification.
- DANA OSGOOD.
